UNITED STATES PATENT OFFICE.

JUAN B. ARCI AND JOHN CHAPMAN, OF BROOKLYN, NEW YORK.

DESIGN FOR A STEAM-RADIATOR PIPE.

SPECIFICATION forming part of Design No. 14,883, dated March 18, 1884.

Application filed January 29, 1884. Term of patent 7 years.

To all whom it may concern:

Be it known that we, JUAN B. ARCI and JOHN CHAPMAN, of Brooklyn, Kings county, New York, have invented a new and original 5 Design for Steam-Radiator Pipes, of which the following is a full, clear, and exact description.

Reference is to be had to the accompanying drawings, forming part of this specification, in 10 which similar letters of reference indicate corresponding parts in both figures.

Figure 1 is a front elevation of our newly-designed radiator pipe, and Fig. 2 is a transverse sectional view of the same.

15 The leading feature of our design consists in making the pipe or tube with shaft, capital, and base portions, like a pillar or column, the shaft being made square in general outline, with longitudinal beads in the center of each 20 panel.

A is the body or shaft portion of a radiator tube or pipe, B is the capital, and C is the base of the tube. The shaft portion A, in general outline, is square, (having four panels, 25 a a,) with the longitudinal beads b b made in the center of each panel, showing the corners c c between each bead. The base C is circular in general outline, and is formed with the horizontal beads or members d d, and with the 30 concave e between the beads d d; and the base is formed also with the plain circular portion f above the upper bead or members d, and with the plain circular surfaces g g above and below the concave e. The capital B is also 35 circular in general outline, and is formed with the plain circular lower bead or member, h, and upper circular member, i, and with the band j between them, having a foliated ornamentation made in relief upon the band, as 40 shown in Fig. 1. At the upper and lower ends

of the shaft portion A, where the same joins the capital B and base C, are formed the inclined angular portions k, which reach down into the angles formed by the longitudinal beads b and panels a, thus giving to the pipe 45 or tube a finished appearance where the orders meet.

Having thus described our design, we claim as new and desire to secure by Letters Patent—

1. The design for a radiator pipe or tube 50 herein shown and described, the same consisting of the body portion or shaft A, ornamented capital B, and ornamental base C, the body portion or shaft A being made square in general outline, with the longitudinal beads b in 55 the center of the panels.

2. The design for a radiator pipe or tube herein shown and described, the same consisting of the shaft portion or body A, showing four panels, a, with longitudinal beads b in the 60 center of each panel, and having the circular capital B and circular base C.

3. The design for radiator - tubes herein shown and described, the same consisting of the shaft A, showing panels a, with longitudinal 65 beads b in the center of each panel, and having base C and circular capital B, having the band j, ornamented in relief.

4. The design for radiator pipes or tubes, consisting of the shaft portion or body A, having four panels, with longitudinal beads b in 70 the center of each panel, and having the capital B and base C, joined to the shaft by the inclines k.

JUAN B. ARCI.
JOHN CHAPMAN.
